(57) **CLAIM**

The ornamental design for a semiconductor element, as
shown and described.

DESCRIPTION

FIG. 1 is a top, front perspective view of a semiconductor
element showing my new design;

FIG. 2 is a front elevational view thereof; and,

FIG. 3 is a rear elevational view thereof.

Portions in broken lines are for illustrative purposes only
and form no part of claimed design.

1 Claim, 2 Drawing Sheets

FIG. 1

FIG. 2**FIG. 3**
